UNITED STATES PATENT OFFICE.

EPHRAIM TRUXALL, OF PITTSBURG, PENNSYLVANIA.

ROLLING-MILL.

SPECIFICATION forming part of Letters Patent No. 672,245, dated April 16, 1901.

Application filed January 9, 1901. Serial No. 42,651. (No model.)

To all whom it may concern:

Be it known that I, EPHRAIM TRUXALL, of Pittsburgh, in the county of Allegheny and State of Pennsylvania, have invented a new and useful Rolling-Mill, of which the following is a full, clear, and exact description, reference being had to the accompanying drawings, forming part of this specification, in which—

10 Figure 1 is a front elevation, partly broken away, showing my invention as applied to the finishing-train of a hoop-rolling mill. Fig. 2 is an end elevation, partly in section; and Fig. 3 is a diagrammatic view of the driving connections.

15 My invention relates to that class of rolling-mills, such as hoop-mills, wherein the top roll is usually driven by its frictional contact with the metal being rolled; and its objects 20 are to prevent the burning of this upper roll, which occurs when the entering end of the metal sticks in the rolls, and to avoid the injury and destruction of the roll which now frequently happens from this cause, and, further, to allow slipping of a frictionally-driven 25 roll and allow for rolls of different diameters.

In the drawings, A represents a finishing stand of rolls, shown as adapted for rolling hoop-iron and consisting of a lower roll 2 and 30 an upper roll 3. The lower roll is positively driven from shaft 4 by wobbler connections 5, a portion of which is broken away in the drawings, as the same is old and well known. The upper roll 3 is driven by exterior friction 35 connections, which will actuate it independently of the friction between it and the lower roll or between it and the metal being rolled and which further allow a slipping of the roll to allow of its surface speed being the same 40 as the surface speed of the lower roll. In the form shown I accomplish this result by belt connections. Thus a belt 6 leads from a pulley portion on the driving-shaft 4 to a pulley 7 on an upper counter-shaft, which is 45 also provided with a pulley 8, from which a driving-belt 9 extends over a pulley 10 on the driving-shaft 11, having wobbler connection 12 with the shaft of the upper roll. The belt 6 is crossed, so as to give proper direction of 50 rotation to the upper roll, and the upper roll

is thus driven by connections which allow a slip where the upper roll differs in diameter from the lower roll.

In order to adjust the spindle 11, I provide end bearings 13 therefor, made in two parts, the 55 lower part being supported upon spiral spring 14, while the upper part is moved up and down positively by shaft 15, having right and left hand screw-threads, with an intermediate squared portion, as shown in Fig. 2. As the 60 upper roll wears smaller in use the bearings for the driving-spindle 11 may be moved down to correspond, giving additional tension to the connecting-belt 9.

In the operation of the device the metal is 65 passed through the rolls in the usual manner and the upper roll is driven by its exterior belt connections, which will allow slip and at the same time prevent any sticking of the entering end of the piece. The burning of the 70 rolls is thus avoided, and at the same time the diameter of the rolls may be different from each other without causing injury thereto.

Many variations may be made in the form and arrangement of the connections for driving the rolls, and the invention may be applied to stands containing two or more rolls, 75 since I consider myself the first to drive a roll by exterior friction connections, such as belts, which allow slipping. 80

I claim—

1. In a rolling-mill, a pair of rolls arranged to receive the metal between them, a positive driving connection for the lower roll, and belt-driving connections from the driving 85 mechanism of the lower roll through a counter-shaft to the upper roll; substantially as described.

2. In a rolling-mill, a pair of rolls arranged to receive the metal between them, a driven 90 shaft having a positive connection with the lower roll, and connected to a counter-shaft which is connected to the upper roll, at least one of the connections for the upper roll consisting of a friction-belt; substantially as described. 95

3. A two-high rolling-mill having a driving-shaft positively connected to the lower roll, a counter-shaft having a belt connection with said driving-shaft, and belt connection from 100

the counter-shaft to the driving mechanism of the upper roll; substantially as described.

4. A two-high mill having a driving-shaft for the lower roll, positively connected with 5 the lower roll, a housing separate from the roll-housing, and a counter-shaft within the separate housing and having belt connections with both the driving-shaft for the lower roll

and the shaft for driving the upper roll; substantially as described.

In testimony whereof I have hereunto set my hand.

EPHRAIM TRUXALL.
